UNITED STATES PATENT OFFICE

JOHN L. HYLAND, OF NEW YORK, N. Y.

SHADE HANGER AND ADJUSTER

Refiled for abandoned application Serial No. 157,593, filed December 28, 1926. This application filed May 20, 1930. Serial No. 454,112.

This invention relates to certain new and useful improvements in shade hangers and adjusters, and is refiled for abandoned application, Serial No. 157,593, filed December 28, 1926. The primary object thereof is to provide novel and improved means for adjustably suspending the shade carrier from the top of the window frame.

A further object of the invention is to provide novel and improved means for holding the shade carrier in its adjusted position and further to provide holding means for the shade carrier which can be adjusted so as to dispose the carrier at a spaced distance from the inner face of the window frame, thereby to enable the shade to be used as a ventilator.

Still further and other objects will be later set forth in the course of the following description.

20 In the drawings:—

Fig. 1 is a front elevation of one form of the invention;

Fig. 2 is a vertical sectional view;

25 Fig. 3 is a front elevation partly broken away and in section of the preferred form of the invention;

Fig. 4 is a top plan view of Fig. 3;

Fig. 5 is an end elevation of the shade carrier of Fig. 3;

30 Fig. 6 is a sectional view through the casing for the shade;

Fig. 7 is an end elevation of the casing of Fig. 3;

35 Fig. 8 is a longitudinal sectional view of the cord carrying roller of Fig. 3;

Fig. 9 is an end elevation of Fig. 8; and

40 Figs. 10, 11 and 12 are sectional views taken on lines 10—10, 11—11, and 12—12 of Fig. 8.

In proceeding in accordance with the present invention, a shade roller 1 of usual construction, having a shade 2 thereon is employed. As shown in Fig. 1 of the drawings, a carrier is provided which is composed of telescopic members 3 and 4, which latter have hollow ends in which are received the upper inturned ends of arms 5. The arms 5 are formed of spring metal and are bent downwardly at 7 and perforated to receive the usual pintles 6 of the said roller. The arms

5 are then bent upwardly at 8 and finally downwardly at 9 and have their lower ends provided with finger grips 10. Rubber shoes 11 are secured to the upper ends of the parts 9 of the arm and are formed to frictionally engage the sides of the window frame F. Set screws 13 are provided to adjust the degree of engagement of the shoes 11 with the window frame sides. Cords 14 are secured to the ends of the telescopic members 3 and 4 and engage through eyes 15 secured to the top of the window frame and are connected to a fastener 16 secured to a side of the window frame, whereby upon movement of the cords, the shade carrier may be adjusted vertically of the window frame. As shown in Fig. 1, the lower ends of the arms 9 are slightly curved inwardly at 17' so as to frictionally grip the sides of the window frame.

It will be observed from the foregoing that by grasping the finger grips 10 the shade carrier can be adjusted vertically as desired, and then secured by winding the cords 14 about the disk fastener 16.

Referring to Fig. 2 of the drawings, it will be seen that by disposing the arms 5 horizontally, the shade 2 will have its roller 1 disposed spaced from the inner face of the window frame F, so as to dispose the shade to function as a ventilator. Obviously, the arms 5 can be disposed at any desired elevation along the height of the window frame so as to cause the curtain 2, which then serves as a ventilator to cover the desired part of the window, and of course at the desired elevation. When so disposed, it will be seen that by lowering the windows, ample ventilation is provided above the curtain 2.

When the curtain 2 functions as a ventilator, in order to hold the latter to the window frame, a curtain strip is provided at the lower end of the curtain which strip is composed of telescopic members 17 and 18, the ends of which frictionally engage the sides of the window frame to hold the shade in place. The telescopic strip 17—18 is secured to the bottom of the shade and takes the place of the usual one-piece wood strip which is common to the art. By virtue of the telescopic connection of the members 17 and 18,

the same may be adjusted so as to snugly engage the sides of the window frame and may be secured at any desired point along the height of the latter.

5 In the preferred form of the invention shown in Figs. 3, 4 and 7 to 12, a casing composed of telescopic tubular parts 20 and 21 is employed, these parts having end plates 22 shown in Figs. 4 and 7, provided with 10 slots 23 to enable attachment to the top of the window frame. A roller 24 is mounted in the parts 20 and 21 forming the casing and has cords 25 attached thereto, the latter depending from the casing and being connected to a casing 26 so as to support the latter. The casing 26 is composed of the tubular telescopic members 27 and 28, the latter carrying a shade roller therein provided with a shade 29. Arms similar to the 15 arms 5 of Fig. 1 are secured to the ends of the casing 26 and function in adjustably supporting the latter as in the instance of Fig. 1 in connection with the carrier 3-4.

20 In order to lay the cords 25 on the roller 24, the latter is mounted to move axially of and rotate within its casing. Accordingly, a screw 30 is mounted in an end plug 31 in the roller 24, the plug having a nut 32 rigidly secured thereto and through which nut the 25 screw is threaded. The other end of the roller 24 is provided with a cap 33 through which projects a rod 34 which latter is formed with keyways 36. Pivoted dogs 37 are carried by the cap 33 and engage in the 30 keyways 36. A central plug 38 is secured to the roller 24 and receives the rod 34 therethrough. One or more tensioning springs may be employed for the rod, in the present 35 instance two being shown at 39 and 40. The roller 24 is provided with an axial groove 25, which latter is formed by indenting the material of which the roller is formed. The nut 32 and the cap 33 are cut out at 41 so as to receive the rib provided by the indenting 40 of the groove 25 thereby to hold the nut 32 and the cap 33. The rods 30 and 34 are rigidly secured to the ends of the members 20 and 21 as indicated at 45.

50 I claim:—

1. In combination with a shade roller carrier and means to connect same for vertical adjustment to a window frame, combined operating and holding means for the carrier connected thereto and having parts engageable with the sides of the window frame to hold the carrier against movement, said last named means including arms connected at their upper ends to the carrier and having 55 shade pintle receiving recesses, said arms having their upper portions bent downwardly, then upwardly and finally downwardly and having said downwardly bent portions provided at their lower ends with finger 60 grips, and friction shoes on the upper ends 65

of the downwardly bent portion of the arms to engage the window frame sides.

2. In combination with a shade roller carrier and means to mount same for vertical adjustment on a window frame, means connected to the carrier and having parts thereof engageable with the sides of the window frame in one position of the carrier to hold the carrier against movement and having other parts engageable with and at any point along the length of the sides of the window frame in a second position of the carrier to hold the carrier spaced from the inner face of the window frame so as to enable the shade to extend downwardly at an incline toward the window frame thereby to serve as a ventilator, and means carried by the bottom edge of the shade and engageable with the sides of the window frame to hold the shade thereto. 70 75 80 85

3. In combination with a shade roller carrier and means to mount same for vertical adjustment on a window frame, means connected to the carrier and having parts thereof engageable with the sides of the window frame in one position of the carrier to hold the carrier against movement and having other parts engageable with and at any point along the length of the sides of the window frame in a second position of the carrier to hold the carrier spaced from the inner face of the window frame so as to enable the shade to extend downwardly at an incline toward the window frame thereby to serve as a ventilator, and means on the bottom edge of the shade and engageable with the sides of the window frame to hold the shade thereto, said last named means including telescopic members secured to the bottom of the shade and movable to engage with and to be disengaged from the window frame. 90 95 100 105 110

4. In combination with a shade roller carrier and means to connect same for vertical adjustment to the window frame and to permit the carrier to be moved to lie spaced from the inner face of the frame, arms connected to the carrier and having parts engageable with the sides of the window frame to hold the carrier adjacent to the latter and having other parts engageable with and at any point along the length of the sides of the window frame to hold the carrier spaced forwardly from the window frame so as to permit the shade to serve as a ventilator, and means carried by the bottom of the shade and engageable with the sides of the window frame at any point along the length of said window frame sides to hold the shade in its ventilator position. 115 120 125

5. In combination with a shade roller carrier and means to connect same for vertical adjustment to the window frame and to permit the carrier to be moved to lie spaced from the inner face of the frame, arms connected to the carrier and having parts engageable 130

with the sides of the window frame to hold the carrier adjacent to the latter and having other parts engageable with and at any point along the length of the sides of the window frame to hold the carrier spaced forwardly from the window frame so as to permit the shade to serve as a ventilator, and means to connect the bottom of the shade to the window frame in the ventilator position of the latter comprising extensible members carried by the bottom edge of the shade and movable inwardly and outwardly so as to be disengaged from and engaged with the sides of the window frame at any point along the length and sides of the window frame.

In testimony whereof I affix my signature.
JOHN L. HYLAND.
